UNITED STATES PATENT OFFICE.

JOHN VASKO, OF HUTCHINSON, WEST VIRGINIA.

RAILWAY-TRACK SWITCH.

1,095,301.

Specification of Letters Patent.

Patented May 5, 1914.

Application filed February 6, 1914. Serial No. 816,952.

To all whom it may concern:

Be it known that I, JOHN VASKO, a citizen of the United States, residing at Hutchinson, in the county of Marion and State of 5 West Virginia, have invented certain new and useful Improvements in Railway-Track Switches, of which the following is a specification.

This invention relates to certain new and 0 useful improvements in railway track switches.

According to my invention, I provide a track switch employing switch tongues that are operated by a switch lever positioned 15 adjacent to and parallel with the track rail so that the switch tongues may be thrown out by a person on the car. This idea is especially advantageous when the switch and its operating mechanism is used in connection 20 with coal or other mining, wherein a brake-man controls the movement of each car.

A further object of the invention is to provide a switch of the trailing type, so that 25 a train or car passing therethrough will not require manual shifting of the switch tongues and to further position the switch operating lever so that the same may be operated independently of the car.

With the above and other objects in view that will appear as the nature of the invention is better understood, the same consists of the novel construction, combination and arrangement of parts to be hereinafter more 35 fully described and then claimed, reference being had to the accompanying drawings by like characters denoting corresponding parts throughout the several views, in which:—

Figure 1 is a top plan view of a railway 40 track switch in which the operating lever therefor is arranged parallel to the track rails. Fig. 2 is a top plan view of a track switch in which the operating lever is arranged at right angles to the switch. Fig. 3 45 is a side elevational view of the switch operating mechanism, showing in section the track rails and switch tongues. Fig. 4 is a cross-sectional view taken on line 4—4 of Fig. 3.

Referring more specifically to the drawings accompanying this application, the reference numeral 10 designates the rail ties of the usual construction and mounted on 55 said ties are the rails 11. The track switch comprises the rails 12 having pivoted thereto as at 13, the switch tongues 14. A switch

tongue bar 15 is suitably-connected to the switch tongues 14 as at 16 so that the switch tongues when operated will move in unison.

As shown in Fig. 1, the operating lever 60 or handle for the switch tongues 14 is arranged parallel to and adjacent a track rail 11 and is supported on the ties 10. The supporting means for the switch operating lever comprises a pair of inverted U-shaped spaced 65 side frames 17 secured by their feet 18 to the ties 10. Extending across the U-shaped frames 17 and secured thereto as at 19 are a pair of bars 20 which contact for a portion 70 of their length and are separated midway thereof as at 21 to provide an opening or passage therethrough. Pivotally mounted in the opening in the bars 20 as at 22 is a lever 23, said lever being bifurcated at its lower end, and having a pin passing through 75 the lower end thereof constituting a pivot for the link 24. The pin is provided with an eye 25 upon each end thereof for purposes to be hereinafter described. Pivotally-connected to the other end of the link 80 24 as at 26 is one end of the switch tongue bar 15. The upper end of the lever 23 has pivoted thereto as at 27, an operating handle or lever 28, the lever 28 being positioned between the inverted U-shaped frames 17 85 and extending outwardly beyond the same. Stops 29 are carried by the U-shaped frames 17 which limit the movement of the handle 28 in its opposite directions of travel. The handle 28 has extending therethrough at a 90 point within the frame 17, a pin provided upon each end thereof with an eye 30 and extending between the eyes 25 and 30 and connecting the same are coiled springs 31. These coiled springs 31 are adapted to hold 95 the operating lever 28 in either of its two extreme positions.

The particular disposition of the switch-operating mechanism shown in Figs. 2 and 3, illustrates the idea of positioning the 100 switch-operating lever at right angles to the rails 11 and in this instance, the switch tongues are operated independently of the car. To provide a support for the frames 17, ties 10' of greater length than the remainder of the ties are provided, the ties 10' 105 also extending beneath the rails 11 to act as the other support for the said rails.

The link 24 shown in Fig. 1 has connected thereto a second link 32, and pivoted to the 110 other end of the link 32 is one end of a bell crank lever 33 pivoted as at 34 to a bar 35.

extending between the ties 10, while the other end of the bell crank lever 33 is pivotally-connected as at 36 to one end of the switch tongue bar 15.

5 In the operation of the frame shown in Fig. 1, a person upon a train or car entering the switch, may readily grasp the operating handle 28, which through the medium of the links 24 and 32 and the bell crank lever 33, 10 will shift the switch tongue bar 15 carrying the switch tongues 14 in the direction desired. The form shown in Fig. 2 is operated independently of the car. When the switch is set in either of its extreme positions, that 15 is, the switch tongues caused to engage either of the rails, a train or car may easily trail therethrough due to the flexibility of the operating mechanism which will permit the switch tongue to move from its adjacent rail 20 and be returned thereto after the car passes through the switch. The springs 31 have a tendency to draw or pull the lower end of the lever 23 toward the operating handle 28 and in doing so, the switch tongue bar connected thereto by the links, as above described, will also be held in its fixed position. When the train or car is trailing through the switch, the lower end of the lever 23 will be moved to a greater distance from the 25 operating handle 28 and during such movement, the springs 31 will be expanded which will cause the operating handle 28 to more positively engage its adjacent stop 29.

While I have shown and described the

preferred embodiment of my invention, I do 35 not wish to confine myself thereto as various forms, modifications and arrangements of the parts as shown may be had without departing from the spirit and scope of the invention as claimed.

40 What I claim as new and desire to secure by Letters Patent is:—

The combination with a pair of switch tongues, and a connecting bar, of an inverted U-shaped frame, a connection between the 45 sides of said frame consisting of horizontal bars abutting for a portion of their length and offset to space said bars apart, a lever fulcrumed at a point mid-way of its length between the spaced bars, and bifurcated at 50 its lower end, a link connected at one end to the switch bar, a pin connecting the opposite end of said link to the lower end of the lever, and provided at its ends with eyes, an operating handle movable between the frame bars and fulcrumed upon the upper end of said lever, eyes projecting from opposite sides of said handle, coil springs connecting said eyes with the eyes of the connecting pin of said lever, and slots on opposite sides 55 of the vertical center of said frame to limit the movement of said handle.

60 In testimony whereof I affix my signature in presence of two witnesses.

JOHN VASKO.
